UNITED STATES PATENT OFFICE.

FRANCIS E. COLLINS, OF CONSHOHOCKEN, PENNSYLVANIA.

DAMPER REGULATOR.

Application filed January 26, 1922. Serial No. 531,850.

To all whom it may concern:

Be it known that I, FRANCIS E. COLLINS, a citizen of the United States, residing at Conshohocken, in the county of Montgomery and State of Pennsylvania, have invented new and useful Improvements in Damper Regulators, of which the following is a specification.

My invention relates to a new and useful improvement in a damper regulator, and has for its object to provide a simple and effective device of this character for opening and closing a damper or valve whereby the draught of a furnace may be controlled automatically as the pressure of the steam or other fluid varies.

Another object of the invention is to provide an apparatus of this character which may be operated by steam, water or air pressure to control the damper for regulating the draught.

A further object of the invention is to provide means for moving the weight along the controlling lever to change the position of said weight relative to the fulcrum of the controlling lever and thereby change the work factor of the weight to prevent the damper from being opened or closed too quickly.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawing forming a part of this application, in which:

Fig. 1, is a side elevation of a damper regulator embodying my improvement with a portion of the cylinder broken away to show the piston therein.

Fig. 2, is an enlarged sectional view of the controlling lever showing the manner of mounting the weight thereon.

Fig. 3, is an enlarged side elevation of a connecting member.

Fig. 4, is a plan view of a bracket for attachment to the piston rod.

Fig. 5, is a similar view of another bracket for attachment to the cylinder.

Fig. 6 is an enlarged vertical section of the valve with a portion of the valve lever

and a part of the bracket illustrated in elevation.

In carrying out my invention as here embodied, 2 represents a shelf or platform on which is mounted a diaphragm casing 3 which encloses a suitable diaphragm mechanism, such as is illustrated in my Patent No. 682,791, dated September 17th, 1901, for operating the controlling lever 4 when the steam pressure rises above or falls below a predetermined pressure which latter is regulated by the weights 5 and 6, the latter being connected directly with the control lever while the former is mounted upon the valve lever 7 connected at its outer end with the control lever as indicated at 8 while its inner end is pivoted as at 9 to a suitable bracket 10 carried by the valve 11 the stem 32 of which is connected to the lever 7. 75

The reference numeral 12 denotes a cylinder in which is mounted a piston 33 having a piston rod 13 connected therewith which in turn is connected with a damper by any suitable or well known means so that said damper will be opened and closed according to the movements made by the piston rod.

The valve 11 has an inlet port 34 to which leads a pipe 35 from a source of water supply under pressure, such as a city water main or an elevated tank, an outlet port 36 to which is connected a pipe 37 leading to the lower part of the cylinder 12 beneath the piston and an exhaust port 38 from which leads the pipe 39 to a point of disposal, such as a sewer or drain. 90

The inlet port 34 and the exhaust port 38 have valve seats 40 and 41 respectively associated therewith and with these valve seats coacts a valve plug 42 carried by the stem 32 whereby either of said ports may be closed or both left open.

The parts enumerated above are well known and form no part of my invention except in the combination to be set forth in the claims and therefore these elements have not been set forth in detail.

In actual practice I have found it necessary to vary the weight upon the controlling lever and in order to do this automatically I provide a movable weight 14 which is hung upon the controlling lever by means of a wheel or wheels 15 slidably journaled between the arms 16 of the weight, the said wheel resting on top of the lever as plainly shown in Fig. 2. 110

To the weight is suitably fastened one end

of a stiff connecting member or rod 17 the other end of said connecting member being pivoted to the arm 18 of the bell crank lever 19 which is pivoted as at 20 to some 5 suitable portion of the apparatus and to the other arm of the bell crank lever is pivoted one end of a substantially vertical connecting member or rod 21 the upper end thereof having a connector 22 in the form of 10 a screw eye or its equivalent which is loosely mounted on the screw 23 having threaded connection with the bracket 24 the latter being mounted upon the piston rod 13 and held in its desired adjustment by a set screw 15 25. This bracket includes a projection 26 with a hole 27 for the mounting of the guide rod 28 which latter slides through a hole 29 in the guide bracket 30 mounted upon the cylinder 12 and held in place by set screws 20 31. This arrangement of brackets and guide rod prevent the piston rod 13 from rotating within the cylinder.

In operation when the steam in the boiler exceeds the predetermined pressure regulated by the weights 5 and 6 the controlling lever 4 will be raised and carry the valve lever 7 with it thus opening the inlet port 34 and closing the exhaust port 38. The water under pressure will then pass through 25 the pipe 37 to the cylinder and impart an upward movement to the piston rod 13 so that the bell crank lever 19 will be actuated through the medium of the vertical connecting member 21 causing the weight 14 to be 30 moved outward along the controlling lever 4 through the medium of the horizontal connecting member 17, but when because of a reduced pressure the controlling lever 4 and its connected valve lever 7 fall the inlet 35 port 34 will be closed and the exhaust port 40

38 opened. This will permit the water in the cylinder to flow through the pipe 37, the exhaust port 38 and out through the pipe 39 to the drain permitting the piston 33 to move downward. As such action takes place 45 the weight 14 will be gradually moved toward the inner end of the controlling lever to remove the additional weight.

Of course I do not wish to be limited to the exact details of construction as herein shown as these may be varied within the limits of the appended claim without departing 50 from the spirit of my invention.

Having thus fully described my invention, what I claim as new and useful is:—

A damper regulator comprising in combination a controlling lever, means for raising said lever, a cylinder, a piston rod operating therein, a weight suspended from the controlling lever and movable lengthwise thereof, a bell crank lever, a stiff horizontal connecting member having one end attached to the weight and the other end pivoted to one arm of the bell crank lever, a stiff substantially vertical connecting member having one end pivoted to the other arm of the bell crank lever, a bracket fastened to the piston rod and to which is attached the other end of the last named connecting member whereby motion is transmitted from the piston rod to the weight, a guide rod fixed to the bracket, and a guide bracket mounted on the cylinder and having a hole therethrough for receiving the guide rod whereby the piston rod will be prevented from rotating.

In testimony whereof, I have hereunto affixed my signature.

FRANCIS E. COLLINS.
